J. ALBERT ET AL

DETACHABLE BACK REST FOR SEATS

Filed Dec. 5, 1925

UNITED STATES PATENT OFFICE.

JOSEPH ALBERT AND HENRY ALBERT, OF MILWAUKEE, WISCONSIN.

DETACHABLE BACK REST FOR SEATS.

Application filed December 5, 1925. Serial No. 73,479.

This invention relates to back rests especially adapted for use in connection with row boat seats, circus seats, stadium seats, and the like.

5 Briefly stated, an important object of this invention is to provide a back rest having simple means whereby the same may be applied to a row boat seat, or the like, without the aid of bolts, nails, or other separate 10 fastening devices, and which may be easily removed from engagement with the seat with a minimum of effort and inconvenience.

Another object of the invention is to provide a detachable back rest which is of 15 highly simplified construction, durable in use, and cheap to manufacture.

Other objects and advantages will be apparent during the course of the following description.

20 In the accompanying drawing forming a part of this application and in which like numerals are employed to designate like parts throughout the same,

Figure 1 is a perspective of the improved 25 detachable back rest applied;

Fig. 2 is a perspective of the improved back rest detached;

Fig. 3 is a detail vertical sectional view 30 through the improved back rest applied.

35 In the drawing, wherein for the purpose of illustration is shown a preferred embodiment of the invention, the numerals 5 designate a pair of U-shaped seat engaging members consisting of upper and lower

straps adapted to engage and embrace a seat 6 of a boat 7, or the like. At this point it might be stated that while the invention is shown applied to one of the seats of a row boat it is not in any way restricted 40 to such application since it is equally adaptable for use in connection with circus seats, stadium seats, and the like.

Figure 2 probably best illustrates that the bight portions of the U-shaped seat engaging members 5 are pressed together and shaped to define bearings 2 for trunnions 3 of the side members 8 of the back.

The sides 8 are joined by cross strips or slats 9 and the lower portions of the sides 50 8 are extended forwardly to define arms 10, the terminal portions of which are extended upwardly and are bifurcated as shown at 11 to form pairs of prongs 12.

Figure 3 illustrates that the prongs 12 55 straddle the forward cross bar 16 which connects the seat engaging members 5 and

then embed themselves in the seat to secure the back rest in place. Particular attention is directed to the fact that the extent to which the prongs 12 may enter the bottom of the seat is limited by the engagement of the bottom of the cut-away portions 11 with the cross bar 16. This prevents the prongs from extending through the seat and possibly tearing the clothing of a person using 60 the seat or possibly injuring his or her person.

In summarizing the invention, it will be seen that the improved back rest consists of a back hingedly connected to a seat engaging member and having what might be said to be a pair of levers which extend beneath and engage the bottom of a seat to firmly attach the improved back rest to the seat without the aid of screws, nails, bolts, or 65 other separate fastening devices, and by the same token the improved back rest may be easily removed from the seat by simply swinging the back forwardly and thereby releasing the prongs 12 from engagement 70 with the bottom of the seat. It may be desired to merely collapse the seat without entirely disconnecting the same and in that case it is merely necessary to swing the back forwardly to an inclined position or, if 75 possible, to a position substantially parallel to the horizontal plane which the seat occupies.

A back rest constructed in accordance with this invention may be easily applied to 80 a row boat seat, a stadium seat, a circus seat, or the like, by simply causing the U-shaped seat engaging members 5 to embrace the seat from the rear edge thereof so as to position the back rest at the rear edge 85 of the seat. The back rest is now swung upwardly so that the prongs 12 are caused to extend into the seat at opposite sides of the forward cross bar 16. The back rest is now held firmly in place and will not 90 slide. Particular attention is directed to the fact that in case the improved back rest is used on a stadium seat the upper straps of the seat engaging members form 95 definite divisions so as to mark a particular 100 seat and thereby avoid crowding.

Figure 2 illustrates that the side members 8 of the back are confined between the seat engaging members 5 and the back is, therefore, prevented from becoming accidentally disengaged from the seat engaging members. In addition to this, the terminals 110

of the trunnions 3 are provided with cotter keys 30 or other suitable fastening devices by means of which the bearings 2 are prevented from slipping off the trunnions.

5 The invention forming the subject matter of this application is capable of a wide variety of mechanical expressions and it is, therefore, to be understood that the form of invention herewith shown and described 10 is to be taken merely as a preferred example of the same and that such minor changes in arrangement and construction of parts may be made as will remain within the spirit of the invention and the scope of what is 15 claimed.

Having thus described the invention, what is claimed is:

20 1. A detachable back rest for seats comprising a pair of connected seat engaging members, the connection between the seat engaging members consisting of a cross bar, a back hinged to said seat engaging members and having prongs adapted to straddle said cross bar and extend into a seat to 25 hold the back rest in place.

2. A detachable back rest for seats comprising a pair of connected seat engaging members, the connection between the seat engaging members consisting of a cross bar, 30 a back hinged to said seat engaging members and having prongs adapted to straddle said cross bar and extend into a seat to hold the back rest in place, and means adjacent the prongs and co-acting with the cross bar 35 for limiting the entrance of the prongs into the bottom of the seat.

3. A detachable back rest comprising a pair of U-shaped seat engaging members having their rear portions formed with

40 bearings, a back having trunnions connected to said bearings, said back being provided with lever arms having upwardly directed terminal portions which are bifurcated to define prongs adapted to enter the bottom of a seat.

45 4. A detachable back rest comprising a pair of seat engaging members having their rear portions formed with bearings, a back having trunnions connected to said bearings, said back being provided with lever arms having upwardly directed terminal portions which are bifurcated to define prongs adapted to enter the bottom of a seat, and a cross bar connected to said seat 50 engaging members and being straddled by said prongs whereby the upwardly directed terminals engage the cross bar and thereby limit the movement of the prongs into the seat.

5. A detachable back rest for seats comprising a pair of seat engaging members having means to embrace a seat, a back hinged to said seat engaging members, said back being provided with forwardly directed 55 attaching arms having terminal portions extended upwardly and bifurcated to define prongs adapted to be extended into the bottom of a seat, and front and rear cross bars connecting said seat engaging members, the front cross bar being straddled by 60 said prongs and being engaged by the terminal portions of said attaching arms to limit the movement of the prongs into the seat.

65 70 75 In testimony whereof we affix our signatures.

JOSEPH ALBERT.
HENRY ALBERT.
